UNITED STATES PATENT OFFICE.

FRANK A. FAHRENWALD, OF CHICAGO, ILLINOIS.

FURNACE.

Application filed January 13, 1926. Serial No. 80,960.

This invention relates to furnaces and has special reference to those furnaces, sometimes denominated "process furnaces" which are used for metallurgical and chemical operations. The objects of the invention are the provision of new, improved and simplified mechanism for stirring, scraping and advancing the substance being treated, whereby the initial cost is reduced, the life is increased, injury consequent upon breakage is minimized, and replacement facilitated.

For example some of these furnaces as employed for the roasting of ore are as much as twenty feet in diameter and forty feet high with a five foot vertical shaft in the center provided with radial arms which overhang circular hearths carried one above the other by the furnace wall. These hearths are provided with discharge openings located alternately near the center and near the periphery and the lower edge of each arm is provided with a plurality of suitable plows or stirring blades adapted to turn the material, keep it stirred, and slowly move it inwardly or outwardly as the case may be, a current of flame or of oxidizing gases being meanwhile produced over these hearths so as to maintain the whole at a temperature of from 1000° to 1850° F. This shaft has heretofore ordinarily been cooled by water or air and the arms also have contained extension conduits for the cooling fluid. Owing to the warping of the arms, the development of flaws, or the loosening of bricks under the influence of the high temperature, it is not an uncommon occurrence for an arm to become wedged and broken off and the breakage of one arm is generally followed by the breakage of all other arms carried by the center shaft at the same level. These arms are generally rigidly bolted to the center shaft in some manner so as to be capable of replacement, but owing to the high temperature of the parts, the replacements of such an arm requires anywhere from a few hours to several days, during which time the entire furnace is out of commission, and in addition the breakage of a water-cooled arm inside a hot furnace is likely to be attended with extreme unpleasantness or danger.

The material heretofore ordinarily employed for these arms has been cast iron, the cooling liquid being trusted to maintain its temperature sufficiently low to keep it within its established strength limits. Suggestions

have heretofore been made to employ instead of cast iron a suitable alloy more resistant to high temperatures, but this change alone offers no sufficient advantages over cast iron to warrant the increased expense, since breakage of the arms by dislodged bricks or by the failure of other arms would still occur as before and with no increased facility of replacement. I have devised, however, a mode of mounting such an arm as to avoid these difficulties of breakage and replacement, thereby rendering feasible the use of the more expensive materials. Briefly stated this invention consists in pivoting the arm to the operating shaft upon a hinged joint, and normally holding the same in operating position by a frangible member adapted to yield upon an excessive stress. A further refinement of the invention consists in mounting the hinge pivot at such an angle relative to the shaft that as the arm is released and swings away from its operating position it is also drawn away from the surface of the hearth to which it is nearest, thereby reducing the danger of wedging or breakage. A preferred embodiment comprehending these and other features of my invention is shown in the drawings accompanying and forming a part of this application, although it will be understood that these are intended to be merely illustrative of the general principles of my invention and are not exhaustive of the detailed constructions possible to be employed.

Fig. 1 is a vertical sectional view illustrating in somewhat simplified form the main features of such a furnace; Fig. 2 is a horizontal sectional view corresponding to the line 2—2 of Fig. 1; Fig. 3 is a perspective view of the inner hinged end of one of the rabble arms showing same in working position; Fig. 4 is a perspective view of the same members after the failure of the frangible member; Fig. 5 is a vertical sectional view of one of the arm supporting members; Fig. 6 is a horizontal sectional view through a modified form of shaft equipped with my invention; Fig. 7 is a side elevation of an alternative type of rabble arm secured to a sectional form of shaft; and Fig. 8 is a top plan view of the arm shown in Fig. 7.

The furnace generally comprises an upright cylindrical body 1, although the same may be horizontal or inclined. In the present embodiment this body is provided at different vertical heights with circular, hori-

zontal shelves or ledges 2—2 constituting hearths extending close to the wall and having circular apertures 3 at the center, and between these with other circular horizontal ledges 4—4 having holes 5 near the furnace outer wall and also having central holes 6 in line with the openings 3.

Vertically extending through the holes 3 and 6 is the upright shaft 7 provided at one end, generally the bottom, with a suitable rotating device as the bevel gear 8 meshing with the driving gear 9, and secured to this shaft above each one of the shelves are one or two or more horizontal arms 10—10 known as rabble arms, their lower edges provided with suitable scrapers or blades 11 and 12 respectively. The blades 11 which sweep over the shelves 2—2 are so arranged as to plow the material towards the center while the blades 12 which sweep over the shelves 4 are arranged to plow the material away from the center towards the discharge openings 5. Raw material, such as ore to be roasted or converted, is fed gradually to the top of the furnace by suitable means such as the spout 55, and heat may, if desired, be supplied to the lower end of the furnace by a suitable furnace indicated at 57 although in the case of sulphurous ores it sometimes occurs that the oxidation of the sulphur provides sufficient heat for the purpose. In any case the furnace wall is provided above each ledge or shelf with closable openings 56—56 of sufficient size to permit the entrance of a man or to enable the replacement of parts therethrough.

The shaft 7 may be made of any desired material which is sufficient to stand the mechanical strain at the working temperature. Heretofore the usual practice has been either, as exemplified in the so-called Wedge furnaces and McDougall furnaces, respectively, to make the shafts of steel or cast iron, shielded either by an external covering of bricks, or internally by circulating fluid. The shaft shown in Figs. 1 and 2 hereof is specifically the Wedge type which comprises a cylindrical metal shell 15 surrounded by bricks as shown at 16 and formed with radial apertures for the reception of the base portions 17 of the rabble arms. Each of these base ends ordinarily comprises a cylindrical member 18 adapted to enter a hole in the shaft and a tapering portion 19 adapted to fit a suitable seat and be secured thereto by any suitable means (not shown). The inner diameter of this shell 15 is ordinarily several feet and in it are located vertical conduits 20—20 for cooling fluid, water or air, suitable connections 21 extending thence to the arm bases which are made hollow and provided with a central partition 22 in order to direct the current.

In order to apply my improvements to a furnace of this nature I make a base por-

tion of size and shape to fit the standard openings in the shaft, but instead of making this portion integral with the arm as in the Wedge furnace, and carrying the fluid circulation ducts clear to the end thereof, I terminate this base portion close to the flange 19 by an imperforate end wall 23 beyond which project at one side the two vertically spaced ears 24—24 apertured for the reception of the hinge pin 25. The arm 10 is made of any desirable section to combine strength with lightness, preferably the well known I-beam with vertical web and flanges at top and bottom. At its base this arm is provided with ears 26—26 matching the ears 24 and similarly apertured for the same pin. In order to hold this arm radial during practical operation of the furnace I provide a suitable frangible member of suitable strength to carry all normal and proper operating loads but so limited in strength as to break before any strain is reached which endangers the other parts. Preferably this member consists of a bolt 27 of suitable metallic composition laid in the notches 28—28 of two ears 29—29 which project, one from the base portion and the other from the side of the arm, the same being sufficiently removed from the hinge pin to separate along a predetermined arc. This bolt is provided at one end with a head 30 and at the other end with a nut or collar 31 which cooperates with the ears to hold the arm against movement. This arrangement, while not indispensable, is highly convenient practically for numerous reasons. In the first place a frangible member operating at high temperature is better ruptured by a pull than by a bend or shear both because such rupture occurs at a more definite and predictable point, and because after rupture it leaves the parts in better condition for replacement. Upon rupture of this bolt for any reason the arm merely swings laterally to the dotted position shown in Fig. 2. The notches 28—28 are easily brought into line with one of the openings 56 by rotating the shaft slowly and whenever this occurs it is easy to apply a new tension bolt by inserting the projecting end thereof into one end of a piece of pipe which is then thrust into the furnace until the bolt drops into its place and the pipe is withdrawn.

Another type of furnace mentioned is the McDougall, a cross section of the shaft being shown in Fig. 6. This shaft consists of a massive column 35, generally of cast iron, having opposed flattened portions 36—36 to which the arms are detachably secured. The interior of the shaft is cooled by moving air or water and ordinarily suitable conduits for cooling liquid are carried out into the arms. To apply my improvements to a furnace of this type, I provide a plate member 37 formed at one side with ears 38

apertured for the hinge pin 39 and at the other side with the notched ear 40 adapted for the reception of the frangible bolt 41. The arm 10 may be made in the same manner as heretofore illustrated, namely with ears 42 at one side for cooperation with the hinge pin and a slotted ear 43 at the opposite side for cooperation with the bolt.

In both the foregoing instances it is still necessary to employ cooling fluid to protect the vertical shaft and this not only entails a very great waste of heat but also, in case water is employed, as usually has to be done when common steel and cast iron are the materials employed, greatly increases the danger of property damage and loss of life in the event of any breakage. In order to obtain the full benefit of my invention it is best to employ a shaft also made of a high temperature alloy and one form which such a shaft may take is illustrated in Figs. 7 and 8 wherein 45 represents a single length of such shaft formed at its upper and lower ends with flanges 46-46 for the attachment 25 of adjacent sections. In this case the ears 48-48 are preferably cast directly on the section as are also the slotted ears, 49, which receive the frangible bolts 50. Owing to the fact that no heed need now be paid to replacement difficulties, it becomes possible to 30 simplify the design, locating the companion ears 51 beyond the end of the arm and in line therewith. I have here shown a bolt 50 of greater length.

In all these cases, however, the hinge bolts are preferably located with their axes making a slight oblique angle with the axis of the shaft so that the lateral swinging of the arm shall not only bring it nearer the periphery of the shaft but shall also tend to lift it gradually away from the hearth and thus decrease the danger of catching anything to produce further breakage. It will be obvious that this effect could be produced either by leaning the pins directly away from the shaft or by leaning them laterally of the shaft, and I prefer the latter arrangement since it produces a more immediate lifting of the arm. In either case it will be understood that this is a refinement 50 of the general idea.

It will be understood that the improvements here described can be employed only if the parts are made of some alloy which will maintain the necessary mechanical strength at the working temperatures. Various alloys have been marketed within the last few years which will serve this requirement and that which I prefer consists of 55 alloys of chromium and iron group metals, preferably with a little silicon and substantially without carbon. A very satisfactory alloy is made of 17% chromium, 2% silicon, 33% nickel and the balance iron, but I do 60 not limit myself to any particular type of

composition of alloy. It is only necessary to employ some type of arm which will withstand the working temperatures without the necessity of cooling fluid, although merely to make the old type of arm of 70 such high temperature material offers no substantial improvement from the practical aspect unless further provision be made for the prevention of accidental breakage such as I have here done. In case of the use of 75 special alloy shafting as shown in Figs. 7 and 8 it is generally best to blow air through the same to moderate its temperature, but water with its inconvenience and dangers 80 can be eliminated.

It will be understood that many changes in detail can be made without departing from the scope of my invention, and all such changes it is my purpose to claim and secure 85 excepting only as my claims are restricted by the prior art.

Having thus described my invention, I claim:

1. In a process furnace, the combination with rabble arms of a driving member to 90 which said arms are attached, such attachment including pivoting provisions and a frangible element normally securing the parts against pivoting movement but adapted to yield upon excessive stress. 95

2. In a process furnace, the combination with a material-supporting hearth and a driving member movable relatively thereto, of a rabble arm attached to said member, ploughing blades carried by said arm in a 100 position to sweep over said hearth, the attachment between said arm and member including a hinge joint, and means including a frangible element for holding said hinge-joint rigid, said element adapted to yield upon excessive stress and permit hinging prior to breaking said arm. 105

3. In a process furnace, the combination with a material-supporting hearth and a driving member movable relatively thereto, 110 of a rabble arm attached to said member, ploughing blades carried by said arm in a position to sweep over said hearth, the attachment between said arm and member including a hinge joint, and means including a frangible element for holding said hinge-joint rigid, said hinge joint being so arranged that after breaking of said frangible element the arm is free to move away from 115 said hearth. 120

4. In a process furnace the combination with an upright hollow body having annular shelves therein constituting hearths and an upright shaft concentric with said hearths, of rabble arms connected to said shaft and projecting over said hearths, such connections including hinge-joints whose axes are approximately lengthwise of said shaft, and a frangible member associated with each of 125 said joints adapted to hold the arms rigid 130

until a predetermined breaking stress is imposed thereon.

5. In a process furnace the combination with an upright hollow body having annular shelves therein constituting hearths and an upright shaft concentric with said hearths, of rabble arms connected to said shaft and projecting over said hearths, such connections including hinge-joints whose axes are 10 oblique both to the shaft and to the planes of said hearths.

6. In a process furnace the combination with an upright shaft and a circular hearth, of rabble arms connected to said shaft and 15 projecting over said hearth, such connection including a frangible element adapted to yield upon excessive strain and permit the arm to move out of operating position, and also including a non-rigid device which supports said arm after the breaking of said 20 frangible element.

7. In a process furnace, a rabble arm having a hinge joint therein, in combination with means for holding said joint rigid, said 25 means including a frangible member designed to yield under predetermined stress.

8. In a process furnace, a shell having 30 openings, a rotatable shaft inside said shell, rabble arms connected to said shaft, such connections including hinge joints, and means for holding said hinge joints rigid, said means including frangible members

adapted to yield upon a given stress and said members being accessible and replaceable from the exterior of said shell by way of said 25 openings.

9. In a process furnace, a shell and a rotatable shaft therein, rabble arms connected to said shaft, such connections including hinge joints adapted and arranged to permit said 40 arms to swing transversely of the shaft, and also including frangible members adapted to prevent hinging movement, said members being located approximately perpendicular to the hinge axes. 45

10. In a process furnace, a rabble arm, a driving shaft therefor, and connections between said arm and shaft including a hinge joint and a frangible member, said hinge joint adapted to support the weight of said 50 arm and said member to hold the same in operating position.

11. In a process furnace, a rabble arm, a driving shaft therefor, connections between said shaft and arm for supporting the 55 weight of said arm, and other connections for holding the same in operating position, the supporting connection comprising a non-rigid member and the other connection comprising a frangible member. 60

In testimony whereof I hereunto affix my signature.

FRANK A. FAHRENWALD.
